UNITED STATES PATENT OFFICE

ADOLF H. SCHAFFERT, OF YOUNGSTOWN, OHIO, ASSIGNOR TO TRUSCON STEEL COMPANY, OF YOUNGSTOWN, OHIO, A CORPORATION OF MICHIGAN

CLOSURE OPERATOR AND LOCK

Application filed December 8, 1931. Serial No. 579,764.

In connection with swinging sashes, vents or other closures, and particularly those which swing outwardly and with which fixed screens are employed, it is very desirable that means be provided for positively locking the closures when in open position, for there is danger when high winds or sudden gusts occur, that they will be slammed sometimes with sufficient force to break the glass or the hinges.

10 The object of the present invention is to provide a structure of this character which is highly effective, and at the same time is extremely simple, so that the sash may be held in various positions, and even if it should occur that in a certain position it is not positively locked, it can only move a short distance before it becomes so locked.

In the accompanying drawings:

20 Figure 1 is a horizontal sectional view through a frame and swinging sash showing the novel holding means applied thereto.

Figure 2 is a bottom plan view of the holding means.

25 Figure 3 is a horizontal sectional view on an enlarged scale through the casing and associated parts.

Figure 4 is a sectional view on the line 4—4 of Figure 1.

30 Figure 5 is a detail perspective view of the bottom wall of the casing.

Figure 6 is a similar view of the top wall.

Figure 7 is a detail view in elevation of the plunger.

35 Figure 8 is a detail sectional view on the line 8—8 of Figure 1.

Figure 9 is a detail sectional view on the line 9—9 of Figure 1.

In the embodiment disclosed, the window-frame is shown at 10, and hinged to one side of the same, as illustrated at 11 in Figure 1, is a swinging sash or vent 12. The frame and vent are shown as of deformed metal, though the material of which they are constructed

45 is relatively unimportant.

Secured to the inner side of the lower cross bar of the frame 10 is a casing which consists of a base plate or bottom wall 13 having upstanding ears 14 on its rear side engaged

55 to the inner side of the frame bar. The distance between the ears 14 as shown in Figure 3 marks the length of a slot 16 formed in the frame bar 10. A top wall 17 is provided with side flanges 18 forming the side walls of the casing and these flanges have suitable lugs 19 that pass through openings 20 in the base plate 13 and are upset, thereby securing the casing members together. The side walls 18 have portions cut away to provide an opening 21, which with the space between the ears 14 of the base plate, provides a transverse passageway through the casing.

60 In this passageway is slidably and swingingly mounted a sash-holding bar 22 which 65 is channeled as shown at 23 and at its outer end has a pivotal connection 24 with a bracket 25 secured to the swinging sash 12. The bar 22 is guided in its movement through the casing by an upstanding post 26 fixed to the bottom wall 13 and having a socket 27 opening through its upper end. This post as clearly shown in Figures 4 and 8 is engaged in the channel of the bar and therefore constitutes not only a slide guide but also one on which 70 the bar has a pivotal movement. The inner end of the bar 22 is preferably provided with an upstanding finger piece 28 formed by an angle piece, one arm 29 of which is fitted in the end of the channel 23 of the bar 22 and 75 is secured by any suitable means as a screw 30.

77 The top wall 17 has fixed thereto an upstanding cylindrical shell 31 in which is slidably mounted a plunger 32 carried by a stem 85 33 that projects above the shell and has a finger piece 34. A coiled spring 35, located in the shell 31 and pressing on the plunger 32, urges it downwardly. The lower end of the plunger is in the form of a stud 36 that 90 is adapted to pass through any of a series of openings 37 formed in the holding bar 22 at various points along the same. The stud 36 moreover is adapted to engage in the socket 27 of the post 26, as will be clear by reference to Figure 4.

95 It will be evident that with this structure, if the plunger is raised, by raising the finger piece 34 the stud 36 will be disengaged from the socket 27 and will be elevated above the 100

bar 22. Consequently the bar can then be freely operated and the sash swung in either direction. When a desired position has been obtained and the plunger is released, if one of the openings 37 of the bar is in line with the stud 36, said stud will pass through such opening and into the socket 27. The bar will thus be positively locked as clearly shown in Figure 4 and the sash will be just as positively held against swinging movement. Should it happen that none of the openings 37 is in line with the plunger, said plunger will then rest on the bar, but it will be evident that if the sash moves the bar will be correspondingly moved and the first opening that registers with the stud will receive the same and consequently automatically lock the sash against further movement.

The structure is simple and effective and not only can be manufactured at relatively small cost, but is readily installed.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

What I claim, is:

1. A closure operator and lock comprising a casing having a top and bottom wall and a passageway between said walls, a channeled closure-holding bar slidably passing through the passageway, a guide for the bar mounted on one of the walls within the passageway and engaged in the channel of the bar, and a locking device mounted on the casing and having a stud that interlocks with the bar to hold it.

2. A closure operator and lock comprising a casing having a top and bottom wall and a passageway between said walls, a channeled closure-holding bar slidably passing through the passageway, a guide for the bar mounted on one of the walls within the passageway and engaged in the channel of the bar, and a spring pressed plunger mounted on the top wall of the casing and having a stud that detachably passes through the holding bar and detachably engages in the guide.

3. A closure operator and lock comprising a casing having top and bottom walls and rear spaced ears forming a rear wall and having openings for the reception of fasteners by which the casing can be secured to a frame, the space between the ears forming a passageway that extends through the casing, a closure operating bar slidably and swingingly extending through the passageway, and a plunger mounted in the casing and engaging the bar to secure it.

4. A closure operator and lock comprising a casing having top and bottom walls and rear

spaced ears forming a rear wall and having openings for the reception of fasteners by which the casing can be secured to a frame, the space between the ears forming a passageway that extends through the casing, said 70 passageway opening through a portion of the inner side and one end of the casing, a side and end wall closing the remainder of the casing, a closure operating bar slidably and swingingly extending through the passageway, and a plunger mounted in the casing and engaging the bar to secure it.

5. A closure operator and lock comprising a mounting member having a passageway, a post located in the passageway, a channeled closure operating and holding bar slidably extending through the passageway and having its channel slidably receiving the post, and means that engages the bar to secure it against movement.

6. A closure operator and lock comprising a mounting member having a passageway, a post located in the passageway, a channeled closure operating and holding bar slidably extending through the passageway and having its channel slidably receiving the post, and means that engages the bar and the post to secure it against movement.

In testimony whereof, I affix my signature.
